DOOR FOR FLOOR FURNACES AND LIKE
HEATING APPLIANCESAmbrose D. Olds, Wichita, Kans., assignor to The
Coleman Lamp and Stove Company, Wichita,
Kans., a corporation of Kansas

Application May 5, 1941, Serial No. 391,976

13 Claims. (Cl. 126—116)

This invention relates to a door for the combustion chamber of a floor furnace or like heating appliance which must be lighted from above the floor in which it is suspended.

In heating appliances of this character, it is difficult to provide a satisfactory door through which the burner of the appliance may be lighted in that the door must close gas-tight with little effort on the part of the operator, otherwise the door may fail to seat properly and, in fact, the operator may leave the door open so that fumes escape directly into the room.

It is, therefore, a principal object of the present invention to provide a door that is attached to the combustion chamber and constructed to prevent replacement of the floor grill when the door is left open.

Other objects of the invention are to provide a simple and inexpensive door construction; to provide a door which seats gas-tight responsive to gravity; to provide a door that has freedom of operation so that it is capable of being self-seated; to provide guide means for facilitating self-centering of the door on its seat; and to provide the door with a sight opening covered by a transparent disk.

In accomplishing these and other objects of the invention, as hereinafter pointed out, I have provided improved details of structure, the preferred form of which is illustrated in the accompanying drawings, wherein:

Fig. 1 is a perspective view of a portion of the top of a combustion chamber equipped with a door embodying the features of the present invention.

Fig. 2 is a longitudinal section through the top of the combustion chamber and door showing the door in closed position.

Fig. 3 is a section through the upper portion of a floor furnace which includes the combustion chamber and showing the door in open position with the door projecting through the floor opening for preventing replacement of the grill without first closing the door.

Fig. 4 is a cross-section on the line 4—4 of Fig. 2.

Fig. 5 is a cross-section on the line 5—5 of Fig. 2.

Fig. 6 is a plan view of the door hinge.

Fig. 7 is a perspective view of the door and its supporting arm shown in disassembled spaced relation.

Referring more in detail to the drawings:

I designates the top portion of a combustion chamber such as used in a floor furnace 2 or similar appliance which is adapted for suspension within an opening 3 of the floor 4 of a room to be heated. In the illustrated instance the furnace includes an outer casing 5 supporting the combustion chamber 6 and an inner

casing 7. The combustion chamber 6 is provided in the bottom thereof (not shown) with a burner (also not shown), and which is adapted to be lighted through an opening 8 formed in the top of the combustion chamber. In the illustrated instance the combustion chamber includes mating sheet metal sections 9 and 10, each having an outwardly extending flange 11 and a substantially semicircular section of a collar 12 at the top thereof of greater depth than the flange 11 so that when the sections are placed in juxtaposition and the flanges 11 welded together the collar forms a circular opening 13 in the top of the combustion chamber through which access may be had to the burner when the floor grill 4' is removed. The upper edge 14 of the collar constitutes a continuous circular seat 15 for a door 16 constructed in accordance with the present invention.

20 The door 16 includes a relatively heavy metal body 17 of larger diameter than the seat 15 to accommodate the edge 14 within an annular groove 18 of the door. The groove 18 has upwardly converging sides 19 and 20 of a circumference to provide considerable space 21 and 22 on the respective sides of the collar edge 14, as clearly shown in Figs. 2 and 4. Fixed within the groove is a gasket material 23 having a substantially flat face portion 24 engaging the seat 15 when the door is closed. Extending through the door is a sight opening 25 having a shoudered upper portion 26 forming a seat for a transparent disk 27 to close the opening 25. From the shoulder 26 the face of the opening 25 bevels downwardly substantially at the same angle as the side 19 to form an annular rib 28 projecting into the door opening. The disk 27 is imbedded in gasket material 29 and is retained in position by a plate 30 bearing against a portion of the gasket material seating on a rim 31 on the upper face of the disk, as shown in Fig. 2. The plate 30 has an opening 32 substantially conforming in diameter to the opening 25 and is provided with laterally extending ears 33 adapted to seat upon shoulders 34 projecting from the sides of the cover, the plate being retained by fastening devices, such as screws 35, extending through openings 36 in the ears of the plate and into threaded sockets 37 in the cover as shown in Fig. 4. The outer portion of the cover curves outwardly and downwardly, as at 38, to cooperate with the side 20 of the groove in forming an annular flange or eave 39.

In order to secure the door to the combustion chamber to prevent removal thereof, I provide the door with a hinge connection 40 so designed as to provide free seating of the door gasket upon the seat 15, now to be described. Spaced laterally from the door opening is a substantially channel-shaped bracket 41 having its leg portions 42 and

43 engaging over the flanges 11 and fixed thereto by spot welding or the like to form the fixed member of the hinge. The movable member of the hinge, or that connected with the door, includes an arm 44 preferably formed of a sheet metal stamping and having a channel-like portion 45, the side flanges 46 and 47 of which are adapted to extend over the sides of the flanges 11 when the cover is in seated position as shown in Figs. 1, 2 and 5. The rear ends of the side flanges terminate in ears 48 and 49 offset from the plane of the flanges as indicated at 50 so that the ears extend freely over the side flanges of the bracket 41 and to provide space therebetween as indicated at 51 so that the hinge is adapted for free operation. The ears 48 and 49 are provided with elongated openings 52 extending transversely thereof and registering with an opening 53 extending through the bracket and the flanges 11 for passing a pivot member such as a cotter pin 54. The cotter pin is thus substantially close fitting in the opening 53, but the slotted openings provide freedom of movement of the hinge arm thereon. The top or web portion 55 of the arm extends above the ears 48 and 49 to form a shoulder 56 which is adapted to seat upon the bracket 41 when the cover is moved to open position as shown in Fig. 3. The side flanges at the opposite end of the arm have upwardly curved edges 57 terminating in a flat plate-like portion 58 of substantially triangular shape to provide apertured wings 59 and 60 wherethrough fastening devices, such as screws 61, are threaded into downwardly opening sockets 62 formed in lateral boss-like extensions 63 of the cover to secure the cover to the arm.

When the cover is raised to open position, the center of gravity thereof passes over the axis of the hinge connection 40 so that the weight of the cover retains the stop shoulder 56 in contact with the bracket 41 to retain the cover in open position with a portion thereof extending above the outer casing 5, as shown in Fig. 3, so that it is impossible to apply the grill 4' as long as the cover is open. To facilitate opening of the cover, it is provided with a substantially loop-shaped handle 64 having its ends anchored in bosses 65 of the cover. When the cover is in closed position, as shown in Figs. 1 and 2, it may seek its position on the seat 15 due to the fact that the slotted openings 52 of the hinge provide movement of the arm 44 in an up and down direction, however, the sides of the slotted openings more closely engage the cotter pin and retain the sides 19 and 20 of the cover groove in properly spaced relation with the seat 15 of the flange 12 and with the cover in substantially coaxial relation with the opening 8. In closed position, the side flanges 46 and 47 of the arm closely engage the flanges 11 of the combustion chamber to prevent lateral movement of the cover on the seat 15 which would ordinarily be possible due to the slight spacing between the sides of the slot-like openings 52 and the cotter pin 54.

The cover may be readily lifted to open position, shown in Fig. 3, so that the stop shoulder 56 on the arm engages the top of the bracket 41 and the cover is thus retained in an out-of-way position during lighting of the burner through the opening 8. After lighting the burner, the cover is moved so that the center of gravity passes over the opposite side of the hinge connection, whereupon the cover drops into seating position over the opening. During this movement the sides 19 and 20 guide the cover into

seated position and the flanges 46 and 47 pass over the flanges 11 to retain the coaxial relation of the cover with the opening so that the cover automatically centers itself, and the seat in the body thereof provides a positive seal to prevent fumes from escaping into the room. The grill may then be put into place over the floor opening, completing the operation. If the door has not been properly closed, but left open as shown in Fig. 3, it will be impossible to replace the grill, thereby assuring that the door is first closed before the grill is applied.

What I claim and desire to secure by Letters Patent is:

15. In a heating device having a combustion chamber provided with a door opening, a door for said opening including, an annular seat member surrounding the opening, a bracket member on the combustion chamber and spaced from the seat member, a closure member engageable with said seat member, a channel-like arm fixed to the closure member and having spaced ears provided with elongated openings, pivot means extending loosely through said elongated openings and through the bracket to hinge the arm to the bracket, and means associated with said bracket and engageable between flanges of the channel-like arm to retain the closure member from lateral movement on the seat member.
20. In a heating device having a combustion chamber provided with a door opening, a door for said opening including, a seat member, a closure member including a weighted body having an annular V-shaped groove to freely accommodate the seat member therein, a gasket material in said groove engageable with the seat member, a channel-like arm fixed to the closure member, a bracket, a lost motion pivotal connection between the bracket and the channel-like arm, and means engageable between flanges of the channel-like arm to cooperate with the V-shaped groove of the closure member for centering the closure member on the seat member.
25. In a heating device, a combustion chamber having a door opening in the top thereof and provided with a seat encircling said opening, a closure member for said opening engaging said seat, a bracket fixed to the combustion chamber, a channel-like arm fixed to the closure member and having spaced ears loosely engaging the respective sides of said bracket, a pivot member extending loosely through said ears and the bracket to hinge the arm thereto, and a guide associated with the bracket and engageable between flanges of the channel-like arm.
30. In a heating device having a combustion chamber provided with a door opening, a door for said opening including, a seat member surrounding the opening, a bracket member spaced from the seat member, a closure member engageable with the seat member, an arm fixed to the closure member, a hinge connection connecting the arm with the bracket, said hinge connection having a relatively loose pivot to effect self-seating of the closure member on the seat member, and guide means associated with the bracket member and engageable with the arm as the closure member approaches the seat member.
35. In a heating device, a combustion chamber having a door opening in the top thereof and provided with a seat encircling said opening, a flange member on the combustion chamber and in a plane extending substantially through the axis of said opening, a closure member for said opening engaging said seat, a bracket fixed to the
40. 45. 50. 55. 60. 65. 70. 75.

flange, a channel-like arm fixed to the closure member and having spaced ears loosely engaging the respective sides of said bracket, and means loosely hinging said ears to the bracket, the channel portion of said arm being engageable with said flange member to retain the closure member coaxial with said opening as the closure member approaches the seat upon closure thereof.

6. In combination with a heating device having a combustion chamber provided with a door opening, a door for said opening including, an annular seat member surrounding the opening, a bracket member spaced from the seat member, a closure member engageable with said seat member, a channel-like arm fixed to the closure member and having spaced ears provided with elongated openings, a pivot member extending loosely through said elongated openings and through the bracket to hinge the arm to the bracket, and means associated with said bracket and engageable between flanges of the channel-like arm to retain the closure member from lateral movement on the seat member when the door is closed, said arm having a stop shoulder engageable with said bracket member to support said arm in substantially vertical position with the center of gravity of the closure member on the side of the pivot member opposite the seat member to retain the closure member in open position.

7. In combination with a floor furnace having a combustion chamber provided with an opening in the top thereof and a removable grill extending over the combustion chamber, a closure for said opening, a relatively long arm connected with the closure, and means pivotally attaching the arm to the combustion chamber for pivotal movement from closing relation with said opening to a position extending into the position normally occupied by said grill to prevent application of the grill when the closure is open, one of said connections having limited free movement in all directions to facilitate seating of the closure member.

8. In combination with a floor furnace having a combustion chamber provided with an opening in the top thereof and a grill extending over said combustion chamber but adapted to be removed for access to said opening, a closure member for said opening and having sufficient weight to effect a seal about said opening, an arm fixed to the closure member, a lost motion connecting means pivotally connecting the arm with the combustion chamber for movement of the closure member from a position closing said opening to a position where a portion thereof projects into the space normally occupied by the grill to prevent application of the grill, and a guide on said combustion chamber engageable with said arm when the opening is closed by said closure member.

9. In combination with a floor furnace having a combustion chamber provided with an opening in the top thereof and a grill extending over said combustion chamber but adapted to be removed for access to said opening, a closure member for said opening and having sufficient weight to effect a seal about said opening, a channel-like arm fixed to the closure member and having a relatively loose pivotal connection

with the combustion chamber for movement of the closure member from a position closing said opening to a position where a portion thereof projects into a space normally occupied by the grill to prevent application of the grill, and a flange on the combustion chamber engageable between flanges of said channel-like arm when the opening is closed by the closure member.

10. In a heating device having a combustion chamber provided with a door opening, a seat member surrounding the opening, a bracket member spaced a substantial distance from the seat member, a closure member having an annular groove, a gasket in said groove engageable with the seat member, a relatively long arm fixed to the closure member, a hinge connection connecting the arm with the bracket member, said hinge connection being loose in all directions, and guide means between the bracket member and seat member for guiding the closure member as it approaches the seat member when the closure member is moved to position for closing said opening.

11. In a heating device having a combustion chamber provided with a door opening in the top thereof, a door for said opening including a seat member surrounding the opening and having a seat located in a substantially horizontal plane, a bracket member spaced a material distance from the seat member, a closure member engageable with the seat, an arm of substantial length fixed to the closure member, a hinge connection connecting the arm with the bracket, said hinge connection having a pivot relatively loose in all directions to permit seating of the closure member when the closure member is dropped from open to closed position, and guide means for centering the closure on said seat.

12. In a heating device having a combustion chamber provided with a door opening in the top thereof, a door for closing the door opening, including a closure member comprising a weighted body, means for hinging the closure member on the combustion chamber at a point spaced from the door opening, said means having a limited lost motion connection in all directions and arranged to support said closure member in open position, and guide means on the combustion chamber adapted to guide the closure member into substantially centering position relatively to the door opening when the door is moved from open to closed position.

13. In a heating device having a combustion chamber provided with a door opening in the top thereof, a seat member surrounding the opening, a bracket on the combustion chamber and spaced a material distance from the seat member, a closure member, an arm, means hingedly connecting the arm with the bracket and arranged to support said arm when the arm is moved past vertical position, means connecting the closure member with said arm, at least one of said connections having limited freedom of movement in all directions, and means on the combustion chamber adapted to co-operate with the arm for guiding the closure member on to the seat member when the arm is returned past vertical position toward the seat member.

AMBROSE D. OLDS.
